MACHINE FOR FASHIONING ANNULAR
SHEET METAL ARTICLES

Frank H. Le Jeune and John E. Copeland, Detroit,
Mich., assignors to Kelsey-Hayes Wheel Company,
Detroit, Mich., a corporation of Delaware

Application August 3, 1936, Serial No. 94,083

10 Claims. (Cl. 153—25)

The invention relates to machines for fashioning annular sheet metal members being more particularly designed for use as a step in the process of forming vehicle wheel rims. It is the object of the invention to obtain a construction adapted to flare and progressively thin the opposite end portions of a cylindrical hoop, leaving the central portion thereof substantially of the original diameter and thickness of metal. To this end, the invention consists in the construction as hereinafter set forth.

In the drawings:

Figure 1 is a side elevation of the machine;

Figure 2 is a vertical longitudinal section therethrough;

Figure 3 is a view similar to Figure 2 showing the parts in different position;

Figure 4 is a view similar to Figure 2 showing a slightly modified construction;

Figure 5 is a view similar to Figure 3 showing the construction of Figure 4;

Figure 6 is a sectional plan view of the construction shown in Figure 2;

Figure 7 is a horizontal section taken on the line 7—7 of Figure 1.

The usual method of forming wheel rims is to first form a hoop of a sheet metal strip having its ends welded to each other. This hoop is then refashioned usually by a rolling process, but in some instances by die pressing. Where the diameter of the hoop is increased there will be a drawing and thinning of the metal, while a decrease in diameter of the hoop tends to upset and increase the thickness of the metal. However, the change in thickness is not dependent solely upon these factors, but is also affected by the manner in which the pressure is applied. The machine forming the subject matter of the present invention is designed to operate upon a hoop which is of an original diameter corresponding to the base or inner periphery of the rim and to flare the opposite end portions of said hoop as the first step in refashioning to the desired cross-sectional contour. It has been found that a hoop so flared will uniformly taper in thickness from the central portion to the opposite ends and will permit of further fashioning without materially altering this taper.

Generally described, the machine comprises a pair of opposed pressing heads A and B which are relatively movable towards and from each other and are guided in this movement by posts C. As specifically illustrated, the head A forms the base which may be mounted on any suitable foundation or may be placed upon the table of a

power press. The head B is movable and may be actuated by the plunger of the press or any other suitable means (not shown). Secured to the heads A and B in axial alignment with each other are opposed annular die members D and D'. Each of these has a cylindrical inner end portion D² and an outwardly flaring portion D³ which portions are connected by an arcuate portion D⁴ tangent thereto. There is also a shoulder D⁵ at the end of the flaring portion.

Between the dies D and D' is an expanding chuck E which is floatingly mounted on the base A but is held in axial alignment with the dies. As shown, this chuck comprises a head F resiliently supported upon springs G surrounding guide rods H which latter extend through bearings in the base and have heads H' for limiting upward movement. The lower portions of the springs G engage recesses G' in the base and thus the head F will be normally supported in a predetermined position above the base. On this head F are a plurality of segmental jaws I. These are radially slidably secured to the head, preferably by T-shaped members J extending through slots J' and secured by bolts J². The upper ends of the jaws I are guided by a disk K having radial slots K' for the passage of securing bolts K². The jaws I have inner faces of segmental conical form which are engaged by a conical wedge member L adapted when depressed to simultaneously actuate all the jaws radially outward. The wedge member L is preferably operated by a fluid motor M, which as shown is mounted upon a depending hollow member O secured at its upper end to the head F. This motor contains a piston P connected by a rod P' with the wedge L, the construction being such that when the piston is moved downward the wedge will be depressed, forcing the segmental jaws I radially outward. On the other hand, when fluid pressure in the motor is relieved, this will permit the upward movement of the wedge and the radial inward movement of the jaws. In expanded position the jaws I overlap the cylindrical portions D² of the dies D and D', but in retracted position they will clear these dies permitting them to move towards each other until their inner ends are in contact.

The operation of the fluid motor is controlled and properly timed with the operation of the press by the following construction: Q and Q' are cam members shown as angle bars, which are secured to a member Q² on the movable head B. R is a piston valve mounted on a bracket R' secured to the stationary head A. S is a plunger

for operating the valve R, and S' is a latch member pivotally mounted upon the plunger and carrying a roll S² for traveling on the cams Q and Q'. The latch member, as shown, is L-shaped and has a horizontal arm carrying the roll S² and a depending arm adapted to abut the plunger and limit rotation of the latch member in a clockwise direction about its pivot. The latch member is normally held in this position by the coil spring S³, but may swing in a counter-clockwise direction. The cams Q and Q' are secured to the member Q² by bolts Q³ which pass through slots Q⁴, thereby permitting of vertical adjustment. The roller S² overlaps the two members Q and Q' either one of which would form a track for said roll during the vertical movement of the head B. Thus, one of the members Q and Q' can be adjusted to control the upper limit and the other the lower limit. In this manner, the timing of the operation of the valve may be varied both as to opening and closing movement.

With the construction as described, the operation is as follows: The hoop which is formed by the welding together of the opposite ends of the sheet metal strip, is seldom of true circular form. However, the chuck E is initially in contracted position and will thus permit the operator to sleeve the hoop thereover, as shown in Figure 1. The mechanism is then set in operation to depress the head B and shortly after its initial movement the lower end of the cam Q will engage the roller S² which will actuate the valve R to supply fluid pressure to the motor M. This will expand the chuck E changing the form of the hoop to that of a true circle and aligning it with the cylindrical portions D² of the opposed annular dies. The further downward movement of the head B will enter the portion D² of the upper die into the upper end of the hoop and will then carry both the hoop and the chuck E downward, this being permitted by the yielding of the springs G so as to sleeve the lower end of the hoop about the portion D² of the lower die, as shown in Figure 2. When both ends of the hoop are engaged with the portions D² of the dies, the chuck will be collapsed by the disengagement of the roller S² from the upper end of the cam Q', thereby permitting the valve R to relieve the fluid pressure in the motor. The jaws I may be moved radially inward by any suitable means. However, to avoid any danger of failure, the upper ends of the jaws I have cam portions I'. These will be in the path of the descending upper die member D' and will operate to move the jaws I radially inward as the member D' descends. From this time on, the hoop is supported solely by the die members D and D', but to avoid the flaring of either end more than the other, the shoulders D⁵ will form limit stops. Thus, the dies D and D' can approach each other until their inner ends contact which will produce a hoop having its opposite ends flared and its central portion of the original diameter. The heads are then moved apart disengaging the expanded hoop from the dies, permitting of removal of the same from the collapsed chuck. By reason of the construction of the latch member S' and its pivotal mounting upon the plunger S, the movement of the head B to move the die member D' away from the die member D does not affect the movement of the valve R so that the motor remains relieved of fluid pressure. This is true because the latch member may swing about its pivot against the resistance offered by its retracting spring S³ when

the roller S² comes into contact with the upper end of the cam Q'.

In Figures 4 and 5, we have shown a slightly modified construction designed for performing the second operation of fashioning the rim. In this construction the annular die members T and T' are fashioned to further expand the flaring portions of the hoop as formed by the first operation and to form the side walls of the well or drop-center of the rim. Also, the chuck F' instead of collapsing to clear the dies, is arranged permanently between the same and forms the limit for their inward movement. The timing of operation differs from that of the machine as first described, in that the chuck after being expanded to engage the central portion of the rim, remains in this position during the operation of the dies and thereby prevents any radially inward deflection of the portion of the rim in engagement therewith. In operation the flared hoop as formed by the first step is placed over the chuck F', while the latter is in collapsed position and is held in registration therewith by resting at its lower end on a supporting bearing U, this being mounted on the floating frame for the chuck and so positioned as to hold the hoop in symmetrical relation to the central plane of the chuck. During initial movement of the head, the chuck F' is expanded to engage the central portion of the hoop after which the dies T and T' engage the flaring portions of the hoop at a point intermediate the ends of said portions. This engagement is by an arcuate portion T² of the dies and as the dies move inward the point of bearing travels along the flared portions while it is refashioning the same. Thus there is no tendency to thin the metal for the friction of the die and its inward movement has on the contrary a slight upsetting effect. The result is that the uniform taper in thickness produced in the flaring portion by the first operation still remains in the refashioned hoop formed by the second operation.

The rim, as formed by the second operation, has a base portion 1 which is substantially the original diameter of the hoop, outwardly extending walls 2 forming the sides of the well, and flaring portions 3. The latter are then further fashioned to form the tire bead seats and the retaining flanges, but as these operations are preferably performed by rolling, they do not form any part of the subject matter of the present application.

What we claim as our invention is:

1. A machine for forming wheel rims comprising opposed presser heads, annular dies mounted on said heads in axial alignment with each other, a chuck axially floatingly mounted between said dies and adapted in collapsed position to receive a hoop, means for relatively reciprocating said presser heads, and means operated by the initial inward movement of said heads for expanding said chuck to circularize said hoop and to hold the same in alignment with said dies whereby upon the further inward movement of said heads said dies will engage the opposite end portions of said hoop and expand the same.

2. A machine for forming wheel rims comprising opposed presser heads, annular dies mounted on said heads in axial alignment and having substantially cylindrical inner end portions and flaring outer portions, a chuck axially floatingly mounted between said dies and adapted in collapsed position to receive a hoop and to clear said dies, means for relatively reciprocating said heads, means operated by the initial inward

movement of said heads for expanding said chuck to circularize said hoop and to permit entrance of the cylindrical portions of said dies into the opposite ends thereof, and means operating upon the further inward movement of said heads for collapsing the chuck to clear said dies whereby during the continued inward movement the flaring portions of said dies will expand the end portions of said hoop while the cylindrical inner 10 end portions of the dies will hold the central portion of the hoop to substantially its original diameter.

3. A machine for forming wheel rims comprising opposed presser heads, annular dies mounted on said heads in axial alignment, each having a substantially cylindrical inner end portion and a substantially straight line outer flaring portion, said portions being connected by an arcuate intermediate portion, a chuck axially floatingly mounted between said dies and adapted in collapsed position to receive a hoop and to clear said dies, means for relatively reciprocating said heads, means operated by the initial inward movement of said heads for expanding said chuck to circularize said hoop and to permit entrance of the cylindrical portions of said dies into the opposite ends thereof, and means operating upon the further inward movement of said heads for collapsing the chuck to clear said dies whereby the continued relatively inward movement of said heads will cause the flaring portions of said dies to progressively expand in diameter and thin in cross section the end portions of said hoop while the cylindrical inner end portions of said dies 30 will maintain the central portion of said hoop substantially its original diameter and thickness.

4. A machine for forming wheel rims comprising opposed presser heads, annular dies mounted on said heads in axial alignment with each other, a chuck axially floatingly mounted between said dies in alignment therewith and adapted in collapsed position to receive a hoop, a fluid motor for expanding said chuck, and timing means controlling said motor for expanding said chuck to circularize the hoop in advancement of the engagement of the dies therewith.

5. A machine for forming wheel rims comprising opposed presser heads, annular dies mounted on said heads in axial alignment with each other, a chuck axially floatingly mounted between said dies in alignment therewith and adapted in collapsed position to receive a hoop, a fluid motor carried by said chuck and adapted to expand the same, a valve for controlling said fluid motor, and timing means for actuating said valve whereby said chuck is expanded to circularize said hoop in advancement of the engagement therewith of said dies.

6. A machine for forming wheel rims comprising opposed presser heads, annular dies mounted on said heads in axial alignment with each other, a chuck between said dies adapted in collapsed position to receive a hoop, said chuck including a head axially floatingly mounted on one of said presser heads, jaws radially movably mounted on said chuck head, a central wedge-shaped member movable axially to expand said jaws, a fluid motor mounted on said chuck head and operatively connected with said wedge-shaped member, a valve controlling said fluid motor, and means for actuating said valve by the relative movement of said presser heads and timed to expand said chuck to circularize said hoop in advance of engagement of said dies therewith.

7. A machine for forming wheel rims comprising opposed presser heads, annular dies mounted on said heads in axial alignment with each other, a chuck axially floatingly mounted between said dies and adapted in collapsed position to receive a hoop, means on the floating mounting for said chuck adapted to hold the same in symmetrical relation to the central plane of the chuck, means for relatively reciprocating said presser heads, and means operated by the initial inward movement of said heads for expanding said chuck to circularize said hoop and to hold the same in alignment with said dies whereby upon further inward movement of said heads said dies will engage the opposite end portions of said hoop 15 and symmetrically expand the same.

8. A machine for forming drop-center wheel rims comprising opposed presser heads, annular dies mounted on said heads in axial alignment with each other and fashioned to form the sides 20 of the drop-center portion of the rim, a chuck axially floatingly mounted between said dies and adapted in collapsed position to receive a hoop, the expanded diameter of said chuck and its axial length being that of the bottom of the 25 drop-center portion of said rim, means on the floating mounting for said chuck adapted to support in symmetrical relation thereto a hoop having a central cylindrical portion and oppositely flaring end portions, means for relatively reciprocating said presser heads to bring said dies into contact with the ends of said chuck, and means operated by the initial inward movement of said heads for expanding said chuck to engage the central portion of said hoop and to hold the same 30 concentric with said dies and against radial inward movement whereby upon the further axially inward movement of said heads said annular dies will refashion said flaring portions to form the sides of the drop-center portion of the rim. 40

9. A machine for forming wheel rims comprising opposed presser heads, annular dies mounted on said heads in axial alignment with each other, a chuck axially floatingly mounted between said dies in alignment therewith adapted in collapsed 45 position to receive a hoop, means for relatively reciprocating said presser heads, means operated by the initial inward movement of said heads for expanding said chuck to engage said hoop and to hold the same in alignment with said dies, and a yielding support for said chuck permitting axial movement thereof toward one of said dies 50 to engage the hoop therewith simultaneously with the engagement of the other end thereof with the relatively moving die. 55

10. A machine for forming wheel rims comprising opposed presser heads, annular dies mounted on said heads in axial alignment with each other, a chuck axially floatingly mounted between said dies in alignment therewith adapted in collapsed position to receive a hoop, means for relatively reciprocating said presser heads, means operated by the initial inward movement of said heads for expanding said chuck to engage said hoop and to hold the same in alignment with said dies, a yielding support for said chuck permitting axial movement thereof toward one of said dies to engage the hoop therewith simultaneously with the engagement of the other end thereof with the relatively moving die, and means 60 for collapsing said chuck to clear said dies in the further movement thereof. 65
